[57] CLAIM

The ornamental design for a hanger or the like, substantially as shown and described.

DESCRIPTION

FIG. 1 is a front elevational view of a hanger illustrating the design;

FIG. 2 is a right hand end view of FIG. 1; and

FIG. 3 is a perspective view showing the hanger in use. The dotted lines shown in FIG. 3 are disclosed for illustrative purposes only and form no part of the claimed design.
